(57) **CLAIM**

The ornamental design for a shoe bottom, as shown and described.

DESCRIPTION

FIG. 1 is a bottom perspective view of the shoe bottom showing my new design;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view.

The Broken lines showing the shoe upper in the figures are for illustrative purposes only and form no part of the claimed design. The broken lines shown on the periphery, in FIGS. 3-6 are understood to represent stitching.
